FOOT-BOARD FOR A BED

Henry G. Zuk, 1431 6th St., Madison, Ill. 62060

Filed Oct. 22, 1965, Ser. No. 87,761

Term of patent 14 years

(Cl. D5—4)

FIG. 1 is a perspective view of a foot-board for a bed, as viewed from the front;

FIG. 2 is a similar view, as viewed from its rear;

FIG. 3 is a rear elevation of the same;

FIG. 4 is an enlarged detail of a portion of the front face of the foot-board; and

FIG. 5 is a front elevation of the foot-board, in reduced scale.

I claim:

The ornamental design for a foot-board for a bed, as shown.
